Primary Examiner — Rachel A. Voorhies*Assistant Examiner* — Benjamin D. Wannemacher(74) *Attorney, Agent, or Firm* — McHale & Slavin, P.A.(57) **CLAIM**

The ornamental design for a rake head, as shown and described.

DESCRIPTION

FIG. 1 is a top front right perspective view of the rake head of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top front right perspective view thereof illustrating an environmental view of the rake head with a handle. The dashed broken lines are for the purpose of illustrating portions of the rake head that form no part of the claimed design.

The dash dot broken lines are for the purpose of illustrating environmental structure that forms no part of the claimed design.

1 Claim, 6 Drawing Sheets(56)
